UNITED STATES PATENT OFFICE.

JOHN H. STOTLEMEYER, OF WILKINSBURG, AND JAMES B. HUNTER, OF PITTSBURGH, PENNSYLVANIA.

RAIL-TIE.

1,177,735.

Specification of Letters Patent.

Patented Apr. 4, 1916.

Application filed August 20, 1915. Serial No. 46,476.

To all whom it may concern:

Be it known that we, JOHN H. STOTLEMEYER and JAMES B. HUNTER, citizens of the United States, residing at Wilkinsburg and Pittsburgh, respectively, in the county of Allegheny and State of Pennsylvania, have invented certain new and useful Improvements in Rail-Ties, of which the following is a specification.

10 Our present invention has relation to certain new and useful improvements in rail ties, and more particularly comprehends novel rail securing means therefor; and as its primary object, it contemplates 15 the provision of a novel device of this nature wherein the body structure is cut out to provide suitable rail seats and improved rail engaging means to be movable longitudinally with respect to the body from a 20 point at the ends of the body whereby a secure connection between the rails and the tie may be attained.

A further object of my invention is to provide a device of the type in question that 25 is extremely simple in construction, strong and durable, and highly practical from both the standpoint of the manufacturer and the standpoint of the user; and which, it is believed, may be manufactured at a comparatively low cost.

Various other objects and advantages will become apparent during the continuance of the following description.

The above and other objects which will 35 become apparent, are accomplished by such means as are shown in their preferred form in the accompanying drawings, described in the following specification and then more specifically pointed out in the appended 40 claims.

In the accompanying drawings wherein like characters designate like parts throughout the several views; Figure 1 is a view in longitudinal section showing our improved 45 rail tie in its preferred embodiment. Fig. 2 is a view in horizontal section. Fig. 3 is a fragmentary view illustrating in detail the method of clamping the rails. Fig. 4 is a view in detail illustrating an improved 50 wedge lock that is employed. Fig. 5 is a view in transverse section showing the relative position of the rail in dotted lines. Fig.

6 is a view in end elevation, the rail also being shown in dotted lines.

In the accompanying drawings, our invention has been shown only in its preferred embodiment and therefore it is to be understood that the following description is only purported to relate to such preferred embodiment.

The numeral 10 designates the body of the tie which is preferably in the form of a tubular metallic structure having its ends closed by caps 11. There is, undoubtedly, a decided advantage in having a tubular body 55 structure instead of a structure square, or oblong in cross section. A structure of this type is not only much more economical to manufacture, but when in use forms a more efficient support for the rails, by reason of 60 its high coefficient of elasticity. Still it will be understood that this is but the preferred embodiment of our invention and that the form of body structure may be varied in 65 consistence with the scope of the subjoined 70 claims.

The body 10 preferably contains a ballast, which, in the present embodiment is shown in the form of a layer of concrete 12 that extends the entire length thereof and approximately half of the height. The added weight at this point serves to retain the body 10 in a certain position and thus facilitates for the proper fastening of the rails such as will be hereinafter pointed out. 75 Further, the body 10 is provided with a pair of cut-outs 13 for the reception of the base portion of the rails 14, the exposed horizontal edges 15 of the body serving as seats for the rails as particularly pointed out in Fig. 90 2. By reason of the fact that the rails rest upon the horizontal edges 15 below the upper edge of the body it will be understood that all lateral movement thereof, commonly known as spreading of the rails, will be prevented. While this structure absolutely 95 eliminates all danger of the spreading of the rails it will be appreciated that the employment of rail spikes or other analogous fastening members is not necessitated. It is 100 of course desirable to provide means for securing the rails in this position particularly to prevent the upward movement of the ends of the rails during the passage of

rolling stock thereover. The structure previously pointed out retains the rails against both lateral and downward pressure. The means that are shown for accomplishing this result consist of a pair of metallic brace rods 15 and 16, one end of each rod being suitably bent as at 17 to engage the base flange of the opposite rails while the other ends are passed through suitable openings in 10 and extend some distance beyond opposite ones in the caps 11. While the rods are so bent as to engage the outer edge of the base flange of the opposite rails 14 each is further provided with a suitably attached 15 clamp 18 which clamps engage the inner edges of the base flanges. In other words each of the rods 15 and 16 is capable of engaging the outer portion of the base flange on one of the rails and the inner portion of 20 the base flange on the other of the rails. Consequently as the free ends of the rods project through opposite caps 11 it will be understood that, by applying the desired stress thereto, the rails may be securely 25 locked in position. To this end each of the rods is provided with a slot 19 adjacent the outer end capable of receiving a wedge shaped locking key.

The preferred form of locking key consists of a pair of wedge shaped members 20 one of which is slightly longer than the other as clearly shown in Fig. 2, and which are secured together adjacent their upper ends by any desired means, such for instance as shown at 21. It will be seen that by driving the wedges into the slots 19, the rods 15 and 16 will be drawn in opposite directions consequently gripping the rails to a greater degree. By spreading the members 20 as shown in Fig. 2 the wedge shaped locking key may be securely retained in its relative position. As one of the members 20 is slightly longer than the other the spreading of the members is greatly facilitated.

Attention is now directed to Fig. 3 of the drawings. As set forth above it is desirable to retain the rails 14 against upward movement. This may be accomplished by 50 the proper formation of the bent portion 17 and the clamps 18. In Fig. 3 the specific formation of the bent portion 17 and the clamp 18 is shown to advantage, it being recognized that each is so formed as to effectually engage the upper edge of the base flange of the rail. This may be accomplished by forming the radius of the bent portions 17 of the rods and the clamps 18 smaller than the radius of the rail base. 55 Consequently it will be seen that a desired wedging action will be exerted on the base flange of the rails.

From the foregoing it is believed that the advantages and novel features of our 60 invention will be readily understood and,

therefore, further detailed description is deemed unnecessary.

In reducing our invention to practice we find that the form referred to herein as the most practical and preferred embodiment is the most efficient, but realizing that certain conditions will necessarily vary in concurrence with the adoption of our device, we desire to emphasize the fact that various minor changes in the details of construction 75 and in the proportion of parts may be resorted to when required without sacrificing any of the advantages of our invention as defined in the appended claims.

Having thus fully described our invention, what we claim as new and desire to secure by Letters Patent is:—

1. In a rail tie, a body structure, means to close the ends of said body structure, said body structure being cut out to provide rail seats, and rail engaging means extending through said closing means to project in proximity to said rail seats, as and for the purpose specified.

2. A rail tie including in combination, a hollow body structure, ballast means arranged in said body structure, caps having connection with the ends of said body structure, said body structure being cut-out to provide rail seats, and rail fastening means coöperating with said caps and extending within said body structure in proximity to said rail sets.

3. A tie including in combination a tubular body structure, caps arranged at the ends of said body structure, ballast means carried within said body structure, said body structure being cut-out to provide a pair of rail seats, a pair of rails engaged with said seats, and means to lock rails in position extending interiorly of said body structure and operative exteriorly thereof.

4. In combination with a pair of rails, a tie including a tubular body structure, caps carried by and closing the ends of said body structure, said body structure being cut-out to provide seats for said rails, a pair of rods carried within said body structure, one end of each rod being upturned to engage the base flange of the opposite ones of said rails, the other end of said rods projecting through opposite ones of said caps, clamps on said rods to engage opposite ones of said rails, and means engaged with said rod to draw the same in opposite directions to lock said rails in position.

5. In combination with a pair of rails, a tie including a body portion, said body portion being substantially circular in cross section, ballast means carried within said body portion, caps carried by and closing the ends of said body portion, said body portion being provided with a pair of cut-outs for receiving said rails, a portion of

said rails extending interiorly of said body portion whereby lateral movement is prevented, and means arranged interiorly of said body portion to lock said rails against 5 upward movement, said last mentioned means being operative from a point exteriorly of said body portion.

In testimony whereof we affix our signatures in presence of two witnesses.

JOHN H. STOTLEMEYER.
JAMES B. HUNTER.
